(57) **CLAIM**

The ornamental design for a shoulder pad, as shown and described.

DESCRIPTION

FIG. 1 is a front view of a shoulder pad;

FIG. 2 is a rear view of the shoulder pad, showing the right side buckle unclasped;

FIG. 3 is a top plan view of the shoulder pad;

FIG. 4 is a right side view of the shoulder pad, showing the right side buckle unclasped;

FIG. 5 is a front perspective view of the shoulder pad as seen from the right side of the shoulder pad, showing the right side buckle unclasped; and,

FIG. 6 is a rear perspective view of the shoulder pad as seen from a left side of the shoulder pad, showing the right side buckle unclasped.

The right side buckle is shown unclasped in FIGS. 2, 4, 5, and 6 in order to show aspects of the design that are not otherwise apparent.

The broken lines represent stitching and do not form part of the claimed design.
